United States Patent Office

Des. 232,251

Patented July 30, 1974

232,251

NOVELTY HAMMER

Leo M. Speight, 47 Pleasant St.,
East Longmeadow, Mass. 01028

Filed Dec. 11, 1972, Ser. No. 314,245

Term of patent 14 years

Int. Cl. D21—03

U.S. Cl. D34—15 A

FIG. 1 is a side elevational view of my new design for a Novelty hammer;

FIG. 2 is an elevational view of one end of the novelty hammer;

FIG. 3 is an elevational view looking at the other end of the novelty hammer; and

FIG. 4 is a bottom plan view of the novelty hammer.
I claim:

The ornamental design for novelty hammer, as shown and described.
